FIG. 1

FIG. 2

FIG.3

FIG.4

FIG.5

FIG. 1 is a perspective view of a take-out snack bar showing my new design;

FIG. 2 is a top plan view thereof;

FIG. 3 is a front side elevational view thereof;

FIG. 4 is a rear side elevational view thereof; and

FIG. 5 is a right side elevational view thereof, the left side elevational view thereof being omitted for brevity in that it differs only in the absence of the cup handle and in the attitude of the spoon handle, as is apparent from the other figures.

The characteristic features of my design reside in an ornamental cup and saucer configuration in which the saucer top constitutes a circular counter extending radially outwardly of serving windows in the cup base, with bar stools arranged radially outwardly of the counter.

I claim:

The ornamental design for a take-out snack bar, substantially as shown and described.
